AMPLIFIER SYSTEM AND METHOD

Application filed August 11, 1931. Serial No. 556,384.

This invention relates to amplifier systems and methods, and particularly to means for changing the amplifying characteristics of an amplifier system.

5 Radio receiving sets are frequently built with a portion adapted to amplify electrical vibration at audio frequency, and with other portions adapted to amplify at radio frequency. As so constructed, the audio frequency portion often does not provide sufficient amplification for use with a phonograph input.

10 An object of this invention is to adapt a radio frequency amplifier portion to use at audio frequencies.

Another object of this invention is to interchangeably and reversibly convert a radio frequency member, or a detector, to an audio frequency amplifier.

15 Still another object of this invention is to switch an additional amplifier stage into the circuit between an audio frequency amplifier and a phonograph pickup.

20 A still further object of this invention is to supply a loud speaker interchangeable at will from a radio signal source and an audio frequency signal source, while converting for the latter purpose a radio frequency amplifier to operate at audio frequencies.

25 A still further object of this invention is to switch from a sound pickup to a radio pickup by a single switch, which both changes the source of signals, changes the number of amplifier stages, and converts a 30 stage from or to radio and audio frequency operation.

35 A still further object of this invention is to switch between a radio frequency signal source and an audio frequency signal source, 40 simultaneously converting an amplifier tube stage from detector operation to audio amplifier operation, and simultaneously to convert a preceding tube system from operation at radio frequency to operation at audio frequency.

45 The objects of this invention are obtained by the use of a double throw switch having a plurality of contacts, in combination with the normal bypass condensers and voltage 50 reducing resistors in an amplifier system.

The double throw switch is adapted to change the bias upon a detector tube to convert it from a biased detector to a normally biased amplifier, at the same time including an audio frequency pickup in the grid circuit of a preceding tube, with a bypass condenser between the first and second stages in combination with the voltage reducing resistors. In the other position of the double throw switch, the audio frequency source 55 is short-circuited, the bypass resistors 60 grounded, and the auxiliary resistance removed to restore the grid bias to normal detector value.

The system thus utilizes a double throw switch, in combination with an audio pickup, a radio pickup, an auxiliary bias resistance, voltage reducing resistors, and a plurality of bypass condensers, to permit a detector and last radio stage to be converted to 65 audio stages supplying other audio stages and a loud speaker, whereby the system is adapted to operate either with audio frequency or radio frequency sources of signals.

70 Other objects or structural details of this invention will be apparent from the following description when read in connection with the accompanying drawing, wherein

75 Figure 1 is a circuit diagram of the essential portions of this invention, and

Figure 2 is a diagrammatic representation of a complete radio and phonograph amplifier system according to this invention.

80 Referring to the figures, the usual radio receiver system may be provided as shown in detail in Figure 2, including a loud speaker 85 1, an output amplifier stage 2, which may be a pair of vacuum tubes connected in parallel or balanced in the so-called push-pull connection, or may be a single tube of any 90 desirable type. The output stage is desirably supplied from a detector 3, which for high quality and efficiency of detection is desirably equipped with means for producing the necessary value of C-bias for detection. 95 However, if desired, it may obviously be equipped with grid leak and condenser for detection. The detector tube 3 has a grid circuit 4, consisting of inductance and capacity. A plurality of radio frequency stages 100

are provided, each having a vacuum tube with grid and plate circuits. In the embodiment shown these stages are impedance-coupled through the condensers shown. However, other coupling means may be utilized in the obvious manner.

The radio system may be supplied with power from a rectifier system as shown, or may be supplied with power from a convenient source as desired. The system thus far described is a representative radio receiver system. To the elements of this system are added certain other elements in a combination outlined in Fig. 1, which permits certain of the stages of the radio system to be used for audio amplification from another pickup to supply the same output amplifier stage and loud speaker.

These added elements may consist of an audio frequency pickup such as a phonograph reproducer 5, the output of which is either directly coupled or transmitted through a repeating transformer 6, with a volume control 7. The secondary of the transformer 6, is connected in series with the resonant circuit 8, to the grid of the last radio amplifier tube 9, and is adapted to be shunted by a pair of contacts in the double throw switch 11. Radio frequency amplifier stages are customarily operated at lower voltages than is required on the final output amplifier stages and the excess voltage is customarily absorbed in a series resistance 12, as shown. Also it is customary to provide bypass condensers from the plate lead to the cathode circuit of both radio frequency amplifier tubes and detector tubes. In the system shown in the figures these bypass condensers are identified by reference characters 14 and 15. These condensers are connected to a common lead which is adapted to be connected through another pair of contacts in switch 11, to ground, and thereby to the cathode circuits.

The necessary grid bias for detection in the detector tube 3, may conveniently be obtained by the flow of current from the cathode lead through a resistance 16, to ground, the value of bias thereby obtained being dependent upon the current flowing, and the value in ohms of the resistance 16. The value of the bias resistance may thus be controlled by switching in and out of the circuit an auxiliary resistance 17, the resistance 17 when connected in parallel with the resistance 16, operating to reduce the circuit resistance in ohms and thereby the voltage drop therethrough effective in producing a bias through the circuits shown on the grid of the tube 3. The resistance 17, may also be connected through contacts in the switch 11.

In the operation of this system, it may function as a normal radio receiver, in which case signals received upon the antenna 18, are inductively transferred to the grid cir-

cuit of the first radio stage vacuum tube 19, as shown, amplified therein, transferred by impedance coupling through the volume control condenser 21, to the grid circuit of the second radio stage vacuum tube 22, amplified therein, further transferred through the impedance coupling condenser 23, to the third radio frequency stage tube 9, and thereafter transferred through a coupling condenser 24, to the grid circuit of the detector tube 3, wherein they are further amplified, detected, and transferred to the output stage 2, for amplification and reproduction in the loud speaker 1.

For this sequence of operations it is essential that the switch 11, be thrown to such a position that the grid circuit 8, of the radio frequency amplifier tube 9, is connected directly to ground and the common lead to the bypass condensers 14 and 15 is also connected to ground. Under these conditions the high impedance of the secondary of the transformer 6, is removed from the grid circuit of the tube 9, which is thereby enabled to function at radio frequencies. Simultaneously the condensers 14 and 15 are adapted to operate as bypass condensers. Condenser 14 thus bypasses any residual radio frequency from the plate circuit coil of tube 9 to the cathode, and condenser 15 bypasses the necessary radio frequency in the grid circuit 4, of the tube 3, to the cathode of tube 3.

For operation with a phonograph pickup the switch 11, may be thrown to the other position.

The pickup 5, is shown as an electromagnetic reproducer adapted to operate on a mechanical phonograph record. It may, however, equally well be a light responsive member operating with a photographic sound record, such as is now in common use with "sound on film" records; alternatively the pickup may be a telephone system, a telephone or telegraph line or any other source of audio frequency signals.

In the embodiment shown the terminals of the pickup 5, are shunted by a volume control resistance 7, and connected to a transformer 6, having an appropriate ratio and impedance for operation in the grid circuit of the tube 9. It may be noted that the secondary of the transformer 6, is connected directly in series with the radio frequency circuit 8. The impedance of the radio circuit to audio signals is, however, so low that the presence of this circuit is immaterial. Accordingly, the signal pickup from the reproducer 5, is advantageously applied to the grid of the tube 9, and the resistance 12, in the plate circuit of the tube 9, is suitable in size and appropriately positioned to operate the tube 9, as a resistance coupled amplifier. Accordingly, the output from the tube 9, passes through the plate coil of the tube which likewise is of too low impedance to affect the audio vibra-

tion to be of consequence, thence through the condensers 14 and 15 which are disconnected from the ground to the grid circuit of the tube 3. Simultaneously, the resistance 17 is connected in parallel with the resistance 16, and the bias produced therethrough reduced to the appropriate value for linear amplification in the tube 3. A portion of the output from the tube 9, may also pass through the 10 condenser 24 to the tube 3.

The audio frequency is thus linearly amplified by the tube 3, and transferred from it to the output stage tubes in the same manner as the detected radio signals, for reproduction in the loud speaker 1.

Thus the switch 11, in one position permits a radio amplifier stage and a detector to function in the normal fashion, and in another position converts a radio stage and a 20 detector stage to linear audio frequency amplifier stages and connects the source of audio frequency signal vibrations to the tube previously operable as a radio frequency amplifier. Thus an amplifier system is enabled 25 to operate at radio frequencies for impedance coupled amplification and detection to the output stage and by means of the transfer switch is also enabled to operate at audio frequency for resistance coupled amplification to supply the same output stage and loud 30 speaker.

The invention above disclosed thus is adapted to operate upon radio frequency signals and upon audio frequency signals with a 35 minimum number of added parts, being essentially only a switch between elements already present plus the necessary signal pickup, and transfer means for the audio signals.

While there is above disclosed but a single 40 embodiment of the device of this invention, it is possible to produce still other embodiments without departure from the inventive concept therein disclosed, and it is, therefore, desired that only such limitations shall be 45 imposed upon the appended claims as are stated therein or required by the prior art.

The invention claimed is:

1. A sound system comprising an amplifier member, means adapted to operate said amplifier at radio frequency, and an auxiliary means adapting said amplifier to function alternatively at audio frequencies.

2. A sound system comprising a radio frequency amplifier member and an audio frequency amplifier member, and means for modifying the characteristics of the radio frequency amplifier to adapt it to operate alternatively at audio frequencies.

3. A sound system comprising a radio frequency amplifier, a detector and an audio frequency amplifier, and means for converting the radio frequency portion and the detector portion to audio frequency amplifier members.

4. A sound system comprising an amplifier

vacuum tube having radio frequency responsive grid and plate circuits, bypass condensers connected thereto, an audio frequency vibration source also connected thereto and a switch member adapted to shunt said audio frequency source and reconnect said condensers. 70

5. The method of operating a vacuum tube amplifier system, which consists in alternatively connecting or disconnecting a source 75 of audio frequency signals in series with a radio responsive grid circuit, and simultaneously isolating or grounding bypass condensers between an output circuit and a following stage. 80

6. The method of operating a vacuum tube amplifier system, which comprises alternatively amplifying therein radio frequency signals and audio frequency signals, reducing the impedance of an input circuit for said 85 radio frequency signals, and converting radio frequency bypass condensers to function as audio frequency coupling condensers for said audio signals.

7. The method of operating a vacuum tube 90 amplifier system, which comprises alternatively amplifying therein radio frequency signals and audio frequency signals, reducing the impedance of an input circuit for radio frequency signals, and alternatively converting radio frequency bypass condensers to 95 function as audio frequency coupling condensers, and modifying the grid bias in a succeeding amplifier stage for audio frequency signals. 100

8. A sound system comprising a plurality of vacuum tubes adapted to operate as a radio frequency amplifier and detector system, and means for converting a radio amplifier and a detector of said system into audio frequency amplifiers, comprising means for connecting a source of audio frequency signals to an input circuit in said amplifier for connecting bypass condensers to function as audio frequency coupling condensers, and for reducing 105 a biasing resistance associated with said detector. 110

9. A sound system comprising a plurality of vacuum tube stages having radio frequency impedances associated therewith, a radio frequency coupled condenser therebetween, a voltage reducing resistor, radio frequency bypass condensers connected therebetween, and a switch member associated therewith adapted to connect said condensers to ground. 115 120

10. The method of increasing the number of stages in an audio frequency amplifier connected to a radio frequency vacuum tube circuit which comprises converting one of said radio frequency tubes into an audio frequency amplifier. 125

In witness whereof, I hereunto subscribe my name this 4 day of Aug. 1931.
